(57) **CLAIM**

The ornamental design for a package for storing an item such as money, as shown and described.

DESCRIPTION

FIG. 1 is a perspective view of the package for storing an item such as money taken from the top right side at the front thereof;

FIG. 2 is a top plan view thereof;

FIG. 3 is a bottom plan view thereof, rotated horizontally from the top plan view shown in FIG. 2;

FIG. 4 is a right side elevational view thereof;

FIG. 5 is a left side elevational view thereof;

FIG. 6 is a front elevational view thereof; and,

FIG. 7 is a rear elevational view thereof.
